UNITED STATES PATENT OFFICE.

EDWIN B. BARTLETT, OF MILWAUKEE, WISCONSIN, ASSIGNOR TO MILWAUKEE STAMPING COMPANY, OF WEST ALLIS, WISCONSIN, A CORPORATION OF WISCONSIN.

DESIGN FOR A TRIMMED LOCK SIDE BAND.

Application filed November 5, 1928. Serial No. 28,763. Term of patent 14 years.

To all whom it may concern:

Be it known that I, EDWIN B. BARTLETT, a citizen of the United States, residing in the city of Milwaukee, in the county of Milwaukee and State of Wisconsin, have invented a new, original, and ornamental Design for a Trimmed Lock Side Band, of which the following is a specification, reference being had to the accompanying drawing, showing isometric view of my trimmed lock side band.

I claim:

The ornamental design for a trimmed lock side band as shown.

EDWIN B. BARTLETT.
